RECORDING DEVICE

Samuel L. Solar, San Jose, Calif., assignor to International Business Machines Corporation, New York, N.Y., a corporation of New York

Application October 18, 1957, Serial No. 691,087

1 Claim. (Cl. 346—21)

This invention pertains to a cyclic information display device and more particularly to an information display device for recording and cyclically displaying transitory information thereon.

According to the present invention, an extremely simplified recording and display mechanism has been provided which is suitable for displaying transitory information of current interest but which information usually requires no permanent record thereof, such as found in recording certain business messages, transactions and inquiries, ground-to-air communications, reservation ticket office operations, and the like. This mechanism, briefly stated, is comprised of an endless belt impregnated with an electrolyte and an acid-base indicator. The impregnant, when subjected to an electric current of one polarity sufficiently varies the pH of the impregnant to provide a colored mark on the belt which disappears upon reversing the polarity. A plurality of styli or electrodes supply a current of a predetermined polarity to the belt for printing human readable characters thereon, matrix fashion, substantially as shown in U.S. Letters Patent 2,457,133. An erasing station is also provided comprising electrodes of an opposite polarity whereby characters recorded, as above, are erased by reversing the acid or alkaline condition of the impregnant.

Accordingly, it is an object of this invention to provide a printing device for erasable recording of information upon a cyclic recording medium.

It is another object of this invention, for reasons of economy, to provide an electrolytic recording mechanism requiring no supply of paper to be continually replenished.

It is another object of this invention to provide a recording mechanism for recording and erasing on a cyclic carrier using a reversible electro-chemical reaction.

Other objects of the invention will be pointed out in the following description and claim and illustrated in the accompanying drawing which discloses, by way of example, the principle of the invention and the best mode which has been contemplated of applying that principle.

The single figure of the drawing is a perspective view of a cyclic information display device according to the invention herein.

The principle of operation of the present invention resides generally in the fact that when any neutral, mildly acid, or mildly alkaline electrolyte is subjected to an electric current, acidification is brought about at the positive electrode while the electrolyte is made alkaline at the negative electrode. A suitable acid-base indicator capable of giving a color change responsive to either an acid or alkaline condition of the electrolyte is added to it. In this manner, the electrolyte can be dyed a predetermined color, dependent upon the indicator used and the polarity of an applied current.

For example, to illustrate the principle, if a piece of filter paper is soaked with a neutral aqueous solution of sodium sulfate (Na_2SO_4) (electrolyte) containing a small amount of phenolphthalein (acid-base indicator), the

2

resulting color of the paper will be white since the neutral solution is clear. If the leads from a battery are pressed against the paper, a pink spot will appear at the cathode indicating a local concentration of hydroxyl ions. Reversing the leads erases the spot by reversing the pH of the solution. Other color producing indicators will, of course, operate in a similar manner.

Referring to the drawing, the display device comprises an endless belt 1 continuously driven by feed sprocket 10 roller 2, the pins 3 of which engage holes 4 along the edges of belt 1. Belt 1 may be of any suitable material; however, a strong fabric having good moisture retention qualities, such as linen, is preferred. Belt 1 is impregnated with a solution of electrolyte and an acid-base indicator. The preferred indicator used happens to be responsive to alkalinity; therefore, writing is done by a cathode and erasing by an anode. However, indicators providing a color change under acid conditions may, obviously, be used in a similar manner, with writing being done by anodes and erasing by cathodes.

The indicator preferred for use in actual practice produces a very dark purple color providing excellent contrast. It is comprised of a mixture of 4 grams of anhydrous sodium sulfate (Na_2SO_4) and 100 milligrams of 25 each of the following ingredients, the mixture being dissolved in 400 milliliters of water and filtered to remove undissolved particles:

Meta-Cresol Purple
Cresol Red
Alpha naphthol benzein

If it is desired, 100 milligrams of Cetylpyridinium Chloride can be added as a preservative.

35 An indicator solution 6, such as described above, is placed in a tray 8 through which belt 1 is drawn via rollers 9, 10, 11 and 12 as feed sprocket roller 2 is rotated counter-clockwise. As belt 1 leaves tray 8, having been immersed in solution 6, excess liquid is 40 removed therefrom by passing it between roller 12 and a squeegee 13.

Belt 1 passes around a guide 15 and onto an anode 16 connected to the positive side of a battery 18. Anode 16 serves to support belt 1 during its upper travel. Belt 1 is fed between anode 16 and a plurality of cathode probes 17 (shown schematically in the drawing). Each of probes 17 is connected to the negative side of battery 18 via a separate switch 19. In this manner the selective closing of switches 19 for various durations will produce human readable characters upon belt 1 by imparting an alkaline condition to the outer surface of belt 1 in the region of probes 19 as they are negatively charged. As shown in the drawing, the letters "S," "E," "L" have been written, the bottom of the letter "U" 55 being in the process of completion, as shown (explaining why the nearest of switches 19 is still closed).

60 Belt 1 continues its counter-clockwise travel, passing over roller 2 and around another guide 21 to an erase station 22. Station 22 is arranged to reverse the pH of the impregnant sufficiently on the outer surface of belt 1 to change the condition created by probes 19, and in this manner erase the printing as explained above. For this purpose, station 22 is comprised of a battery 28 connected to an anode 26 contacting the writing surface 65 of belt 1 and a cathode 27 (in the form of a roller) located on the opposite side of belt 1. Cathode 27 is connected to the negative side of battery 28 via a switch 29 for controlling erasing at station 22. By suitably coordinating switches 19 with erasing switch 29, some 70 parts of the printing on belt 1 can be displayed repetitiously while others are erased.

From station 22, belt 1 is guided beneath a guide plate.

31 into tray 8 for re-impregnating it with solution 6. From here another printing cycle is begun.

While there have been shown and described and pointed out the fundamental novel features of the invention as applied to the preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claim.

What is claimed is:

A cyclic information display device comprising an endless linen belt, a plurality of guides supporting said belt, said guides defining a closed cyclic path, means for driving said belt continuously along said path, said driving means including both a line of holes in and along said belt and a coacting feed sprocket roller having a plurality of pins extending outwardly therefrom for engaging said holes to drive said belt, an acid-base indicator bath in said path for impregnating said belt, said bath including an aqueous solution of anhydrous sodium sulfate, Meta-Cresol Purple, Cresol Red, Alpha Naphthol Benzein and Cetylpyridinium Chloride, said guides being further arranged to pass said belt through said bath, a squeegee 25 in contact with and disposed across said belt and placed to remove excess quantities of said bath from said belt as said belt leaves said bath, said belt having an inner and an outer surface thereto, an information recording circuit in said path including a first direct current voltage
